UNITED STATES PATENT OFFICE.

FRANK GLASNER AND GEORGE ELLISON, OF HINTON, IOWA.

FOLDABLE DRINKING-CUP.

1,253,168.

Specification of Letters Patent. Patented Jan. 8, 1918.

Application filed June 23, 1916. Serial No. 105,481.

To all whom it may concern:

Be it known that we, FRANK GLASNER and GEORGE ELLISON, citizens of the United States, residing at Hinton, in the county of 5 Plymouth and State of Iowa, have invented new and useful Improvements in Foldable Drinking-Cups, of which the following is a specification.

This invention relates to an improvement 10 in foldable drinking cups.

In carrying out our invention we propose to produce a cup of flexible water-proof material which is normally sustained in a suitable casing in a practically air-tight condition so that danger of the same being contaminated by dirt, etc., will be effectively overcome but which may also be easily and quickly projected from the casing when in use.

20 It is a further object of the invention to produce a drinking cup of a size sufficient when folded to be carried in the vest pocket of the owner or to be attached to the said pocket, the cup member proper being at all 25 times inclosed in a plastic casing when not in use and being so associated with the casing as to form a part of the same, and whereby upon a manipulation of a turnable member connected with the casing, the said 30 cup will be forced outwardly from the said casing when the said cup may be readily and quickly inserted in the casing when desired.

It is a still further object of the invention 35 to produce a sanitary drinking cup comprising a flexible or textile water-proof member that is connected with a suitable shaft journaled in a two-piece casing, one of the members of the said casing being also connected with the flexible cup and being 40 hingedly secured to the other member of the casing, the cup being provided at the mouth portion thereof with means whereby the same may be sustained in a cylindrical condition, while a turnable member is connected 45 with the shaft whereby upon the operation of the same the textile cup will be folded around the shaft, and the swinging member of the casing removed to closing position upon the stationary member of the casing, 50 means comprising a movable cap being provided for locking the sections to inclose the cup in the said casing.

With the above and other objects in view

the improvement resides in the construction, combination and arrangement of parts set 55 forth in the following specification and falling within the scope of the appended claims.

In the drawing:

Figure 1 is a perspective view of the improvement, the textile cup being arranged 60 within the casing and the sections of the casing being folded and locked together,

Fig. 2 is a central vertical longitudinal sectional view through the same,

Fig. 3 is a sectional view showing one of 65 the members of the casing swung away from the other member and the cup in its set up position, and

Fig. 4 is a top plan view of the device as 70 illustrated in Fig. 3.

The improvement contemplates the employment of a split metal tube comprising two similar sections 1 and 2 which, when their edges contact, provide a member that is circular in cross section. The members 1 and 75 2 adjacent what I will term the lower edge of the tube are pivotally connected, as at 3, and the said tubes have arranged upon both of their open ends flanged cap members 3' 80 and 4 respectively. The cap member 3' 80 which is arranged at the top of the tube may be provided with a false bottom that has a central opening providing a bearing for one end of a rod or shaft 5, while the opposite end of the said shaft is approximately centrally secured to the lower cap 4. 85 The lower cap is of a greater diameter than the upper cap and is revoluble around the tube, for a purpose which will presently be apparent. The numeral 6 designates a 90 spring member which is secured to the extension 1 and which exerts a tension or pressure between the said section 1 and the section 2 of the tube, whereby to swing the said section 2 upon the pivots 3 outwardly 95 and angularly of the section 1 when the cap 3' is raised to bring its flange out of engagement with the upper edge of the said section 2 of the tube. Preferably the upper end of the section 1 of the tube is extended beyond 100 that of the section 2, so that the cap cannot be drawn entirely off of the said section 1, the upper end of the shaft 5 being provided with a knob or flange 5' to limit the movement of the cap 3', while surrounding the 105 shaft and exerting a pressure between the

flange 5' thereof and the false bottom 3^a of the cap 3' is a helical spring 5^a. The shaft 5 is preferably slit longitudinally, the said slit being devised to receive one edge of the 5 substantially cone-shaped body of a cup 7. It is, of course, to be understood that the cup member 7 may be secured to the shaft in any other desired manner. This cup may be constructed of rubberized silk or may be 10 of any desired elastic or flexible material, the same being water-proof and the said cup 7 is also secured to the inner face of the section 2 of the tube. By this arrangement it will be noted that when the cap 3' is actuated to permit of the spring 6 exerting a tension against the section 2 of the tube the said section will be swung outwardly at an angle to the section 1 drawing from the tube the cup member 7. The cup 7 is connected to the 15 section 2 of the tube only at the upper portion of the said section and has arranged therein, at its connected portion, a pair of spring arms 8 and 9 respectively. These arms are normally flat and have one of their ends pivoted, as at 10, to both the cap and to the upper end of the section 2 of the tube whereby the said sections may normally swing one over the other against the inner face of the cup so that when the cap 4 is turned to 20 revolve the shaft 5, the textile or flexible cup will be wound around the said shaft and such a winding will gradually draw the hinged section 2 of the tube inwardly of the section 1, when the cap 3' may be moved downwardly to lock the section 2 upon the section 1. The spring arms 8 and 9, however, are adapted to provide reinforcing elements for the mouth of the cup whereby to round the 25 said mouth and to accomplish this each of the spring members 8 and 9 is swung in a line with the upper edge or mouth of the cup and their free ends are brought to contact with the shaft 5. The section 2 is then moved inwardly toward the section 1 until 30 the spring members 8 and 9 are bent each to an approximately half circle. To hold the device in this position we provide upon the cap 4 a catch member 11 which has one of its ends pivotally secured to the said cap 4, as at 12. The free end of this cap may be 35 provided with a lip 13 and this lip is adapted to engage in a depression 14 in the outer face of the section 2 of the tube. By reference to the drawing it will be noted that the catch member 11 is curved in plan to conform to the shape of the cap 4 against which it normally engages, and the said cap may be provided with a notch 15 to receive the end of the said cap to hold the same against the 40 cap when the said catch is not swung to engage in the notch 14.

The operation of the device may be briefly described as follows: When the cup is to be brought to use the cap 3' is raised against 45 the pressure of the spring 5^a so that the

flange of the same is elevated above the top edge of the section 2 of the cup. The spring 6 has a tendency to swing the section 2 outwardly to the position illustrated in Fig. 2. The bottom cap 4 is turned 50 to revolve the shaft 5 to permit of the unwinding of the flexible body of the cup 7 from the shaft. When the cup is brought to its outer position as illustrated in Fig. 2 the spring members 8 and 9 are swung upon 55 their pivots to bring the same adjacent to the edges of the said cup, and as previously stated the section 2 is moved or swung from the top thereof toward the shaft or toward the section 1 to permit of the said 60 spring members 8 and 9 bending themselves to provide each a substantially U-shaped member and to also conform or bend around the edges of the section 2. The ends of the springs 8 and 9 contact with the shaft at 65 the opposite sides thereof, or the same may be secured to the said shaft if desired, and when the said spring members 8 and 9 are thus sprung or bulged the lip 13 of the cap 11 is brought to engage with the depression 90 14 of the tubular section 2, holding the section 2 at a desired angle with respect to the remainder of the device and also retaining the springs 8 and 9 in their rounded or sprung condition. After the cup has 95 been used the catch member is swung away from engagement with the tube section 2 and the cap member 4 is revolved around the section 2 of the tube, causing the cup 7 to be wrapped upon the shaft 5. When the 100 section 2 is brought adjacent to the cap 3', the said cap is moved outwardly of the shaft 5 against the pressure of the spring 5^a, the cap 4 in the mean time being continually turned to permit of the edges of the tubular section 2 contacting with the edges of the section 1, when the cap 3' is released to permit of its flange engaging with the upper and outer edge of the tubular section 2.

The device is extremely simple and may 110 be highly ornamental and preferably the section 1 of the tube is provided with a spring clip 16 whereby the device may be suspended from the pocket of the user. The manner of folding the cup within the tube 115 and around the shaft 5 will have a tendency to wring the moisture from the cup and when the cup is inclosed within the tube the same is effectively protected from dust, dirt, air or any foreign matter which might affect 120 the same. Either the cup or the covering member therefor may have printed thereon suitable advertising matter if desired.

Having thus described the invention, what we claim is:

1. In a device for the purpose set forth, a tube comprising two hinged sections, a shaft revoluble in the tube, a textile substantially cone-shaped cup connected to the shaft and to the free end of one of the tube sec- 130

tions, and means for locking and closing the sections to inclose the cup within the sections when the said cup is not in use.

2. In a device for the purpose set forth, 5 a tube comprising two similar sections hinged adjacent one of their ends, a shaft arranged longitudinally of the sections, supporting members for the shaft, spring means for normally swinging one of the sections 10 away from the other section, means for locking the sections together, and a textile cup secured upon the shaft and connected with one of the swinging sections of the tube adjacent the free end of the said section.

15 3. In a device for the purpose set forth, a tube comprising two similar sections, flanged caps upon the ends of the tube, one movable to engage with both of the sections of the tube and the other rotatable around 20 the tube, a shaft arranged centrally of the tube and having one of its ends journaled in a bearing in the slidable cap and its opposite end secured to the turnable cap, spring means for normally swinging one of the 25 sections away from the other section, a cone-shaped textile cup secured to the shaft and having its outer end connected to the swinging section of the tube adjacent the free end thereof, and whereby when the turnable 30 cap is operated to revolve the shaft the tex-

tile cup will be wound around the shaft and the swinging section of the tube will be moved against the other section thereof.

4. In a device for the purpose set forth, 35 a split tube, the sections of which being pivotally connected adjacent one of their ends, a slidable cap upon one of the ends of the tube, a revoluble cap upon the other end of the tube, a shaft arranged centrally of the tube secured to the revoluble cap and journaled in the slidable cap, spring means for swinging one of the sections of the tube outwardly of the other section, a textile cup secured to the shaft and having one of its 40 ends connected to the other end of the swinging section of the tube, a pair of flat spring members pivotally secured in the mouth of the cup and adapted to be arranged upon the said mouth to be compressed by a pressure upon the swinging section of the tube toward the stationary section thereof, a catch member upon the revoluble cap, to engage 45 with the swinging section of the tube to hold the same in the last mentioned position, and a clip upon the stationary member of 50 the tube.

In testimony whereof we affix our signatures.

FRANK GLASNER.
GEORGE ELLISON.
